Claims priority, application Netherlands May 20, 1953

9 Claims. (Cl. 260—683)

This invention relates to the preparation of olefins, and particularly to the production of olefins by the cracking of high boiling hydrocarbons.

It is known to prepare olefins by thermal cracking, in the vapor phase, of high boiling hydrocarbons, or mixtures containing them. As starting material hydrocarbons oils with high molecular weight are used, which boil below about 450° to 500° C. However, it has hitherto been impossible to use in such vapor phase cracking processes higher boiling and less expensive initial materials, such as residues which boil above 450° C. and are obtained when distilling petroleum or petroleum products, on a technical scale, since such initial materials during the required heating to cracking temperature and in the cracking process itself give rise to the formation of large quantities of carbonaceous deposits which tend to clog the cracking equipment.

In such thermal cracking processes heating of the starting material generally takes place indirectly, the heat required to raise the material to be cracked to the cracking temperature being supplied through a metal wall. This procedure, however, involves serious drawbacks. Thus very heavy demands are made on the material of the wall through which heat transmission is effected, especially when cracking is carried out at very high temperatures, for example 600° C. or even higher, and to this end special types of steels are required, which are costly. Another drawback is that—especially when it is desired to obtain high yields of non-branched olefins from starting materials containing predominantly normal paraffins—the time required to raise the material to be cracked to the cracking temperature should be so selected as to be as short as possible to avoid undesirable changes in the initial material, and that when high temperature gradients are employed to this end, there is the danger of overheating the starting material, with the result that nevertheless undesirable reactions may occur.

These undesirable reactions consist in a structural change of the hydrocarbon molecule, for example, a skeleton isomerization in the case of n-paraffins. Since such isomerizations increase as the temperature at which evaporation of the starting material is carried out is higher, and are also strongly catalyzed by carbon deposits, they are more pronounced with higher boiling initial materials than with lower boiling ones. Furthermore, the conventional recycling of non-cracked material, whereby this is thus repeatedly raised to a high temperature, is accompanied by a considerable decrease in the quality of the initial material.

In the case of cracking lighter hydrocarbons, such as ethane and the like to produce ethylene and the like, and such as lighter and readily vaporizable hydrocarbon distillates, such as naphtha or gas oil to produce gasoline and gaseous hydrocarbons, including olefins such as ethylene, it has been shown that the preheated hydrocarbon feed material can be effectively heated by admixture with a large proportion of superheated steam (1700° F. or higher) to an effective cracking temperature. (King and Warburton, Petroleum Processing, November 1952, pages

2

1644-7; Carpenter and Fowler, Petroleum Refiner, volume 31, No. 4, April 1952, pages 148-9.) However, the production of the large quantities of high temperature superheated steam requires heat transfer through the walls of the tubes of the superheater.

Various proposals have been made for the use of circulating masses of particulate refractory material, as in pebble heater and reactor systems and the so-called thermofor process, for the thermal cracking of various petroleum materials to produce gasoline, olefins, aromatics, and the like, wherein the necessity of transferring heat to the reactants through a metal wall is obviated. It has also been proposed to utilize fluidized systems of heat-carrier refractory materials for the pyrolysis of hydrocarbonaceous materials. However, none of these methods are entirely satisfactory, particularly for the cracking of high boiling hydrocarbons for the production of olefins.

It has also been proposed in some earlier patents, e. g., U. S. 1,274,976 as well as some more recent patents, e. g., U. S. 2,587,703, to provide the heat necessary to maintain the desired temperature necessary to effect an efficient endothermic cracking reaction, by mixing the material being processed with a controlled proportion of oxygen, as air, to effect the oxidation of a part of the material in an exothermic reaction. However, the operations of even this latest development of the so-called autothermic process leave considerable to be desired, possibly because of some important differences in the factors which determine the optimum conditions for the exothermic oxidation and in the factors which determine the optimum conditions for the thermal cracking to produce the desired olefins.

It has now been found that products rich in olefins may be prepared most advantageously, while avoiding drawbacks of previous methods, by bringing high boiling hydrocarbon mixtures, containing less than 25% by weight of aromatics, very quickly to a temperature of not lower than 500° C. by direct heating, effected by completely burning, in the atmosphere of the material to be cracked, a part of the said material in a relatively small heating zone which precedes the actual cracking zone and in which there is an oxidation-promoting solid, and then passing the vapor mixture effluent from the heating zone through the cracking zone.

It has been found that when proceeding in this manner the material to be cracked is raised so quickly to cracking temperature that undesirable changes in the initial material and side reactions may be entirely or practically entirely avoided.

As already indicated, it is true that cracking processes have been known before in which direct heating was applied by burning a part of the material in the atmosphere of the material to be cracked, but it has been found, according to the present invention, that in order to obtain products with a high content of olefins, particularly higher straight chain olefins, it is necessary to carry out this direct heating in the presence of an oxidation-promoting substance, preferably comprising a solid variable-valence metal oxide, and starting moreover from hydrocarbon material having an aromatic content of less than 25% by weight, and then to effect the cracking in a separate zone in the absence of oxidization catalyst.

Thus, in the process according to the invention, part of the material to be cracked which is supplied to the heating zone is completely burned with free oxygen to form water, carbon dioxide and/or carbon monoxide and the heat evolved by this exothermic combustion very quickly raises the temperature of the entire mass of the mixture, preferably in a fraction of a second, to cracking temperature, i. e., to at least 500° C.

Combustion may be effected by any suitable gas which sustains combustion, such as oxygen or free oxygen-containing gases, particularly air, or other gases having an oxidizing effect, such as nitrogen oxides or ozone, or

mixtures thereof. The part of the starting material which is burned will vary with the cracking temperature to be applied and the degree of cracking. In general combustion of not more than about 10 to 15% by weight of the supplied material will suffice.

Examples of suitable substances which promote oxidation include those having a large active surface area, for instance, an area of more than 40 square meters per gram, such as activated alumina, bauxite, silica gel, titanium oxide, cerium oxide, thorium oxide, chromium trioxide, vanadium pentoxide, oxides of cobalt or manganese, or mixtures or combinations of two or more of these substances. It is preferable to use a strong oxidation catalyst, for example, vanadium pentoxide, which is suitably applied to a carrier, such as activated alumina, 10 silica gel, fragments made from bauxite, silicates, etc.

The use of such substances having a large active surface area greatly assists combustion and ensures extremely rapid and uniform heat transmission to the hydrocarbon material passing through the heating zone while moreover the capacity of this zone, as compared to that of the adjacent but distinct cracking zone, may be small, so that the residence time of the material in the heating zone under highly active oxidizing conditions may be only a small fraction of the residence time of the material in the cracking zone under essentially non-oxidizing conditions. The ratio of the capacity of the heating zone to the cracking zone generally lies between about 1:8 and 1:100, a particularly effective ratio being between about 1:15 and 1:50. The heating and the cracking spaces can be made from comparatively cheap materials, such as ordinary steel, the heating space being conveniently provided on its inside with a refractory lining.

The hydrocarbon vapors heated to cracking temperature in the heating zone are passed directly and immediately into the cracking zone, in which the hydrocarbon molecules by a purely thermal vapor phase cracking decompose into smaller fragments, products with a high olefin content being thereby produced.

As starting material for the process of the invention, any type of high boiling hydrocarbon mixture (i. e., boiling above about 300° C.), which may be of natural or synthetic origin, may be used, provided it does not contain more than 25% by weight, and preferably a maximum of 15% by weight, of aromatics. Initial materials having a higher aromatic content have been found to be unsuitable because they cause pronounced carbon deposits to form in the heating and cracking zones, which give rise to serious interruptions to operation.

The aromatic content is readily determined by percolating a sample of the hydrocarbon mixture over silica gel and then desorbing the non-aromatics by washing the silica gel with a low boiling saturated hydrocarbon, for example n-hexane, after which the portion of the sample left on the silica gel is regarded as aromatics.

The composition of the non-aromatic part of the initial material, which may consist of normal paraffins, isoparaffins and naphthenes, is of secondary importance if it is intended to prepare mainly olefins with lower molecular weight, that is to say, with less than 6 carbon atoms per molecule. However, this is not the case when it is desired to produce mainly higher olefins. In order to obtain a cracked product with a high content of higher olefins, in particular those with a straight chain, it has been found to be desirable that the starting material should have a content of higher paraffin molecules or radicals of more than 40% by weight, preferably more than 60% by weight. These paraffins may not only occur as normal alkanes but also in the form of straight chains which are bound to hydrocarbons of different structure, for instance as in a higher n-alkylnaphthene.

Examples of suitable initial materials are high boiling, mineral oil fractions poor in aromatics, or Fischer-Tropsch higher hydrocarbons, paraffin wax distillates or other

material rich in paraffin wax such as paraffin wax obtained when dewaxing lubricating oils, and the like.

A special advantage of the process of the invention is that it provides a method whereby cheap initial materials 5 which are abundantly available may be used as starting material, such as residues boiling above 450° C. which are obtained when distilling mineral oils or mineral oil products, and which could not be processed in the vapor phase cracking processes heretofore employed.

The starting material to be converted may be conveniently preheated, decomposition with the formation of carbon deposits being preferably avoided. If the starting material is not liquid, owing to the presence of normally solid paraffins, it must be sufficiently preheated to liquefy it.

The temperature at which the starting material is heated in the heating zone and also the residence time of the vapor mixture effluent from that zone in the cracking zone will depend on the nature of the olefins which are 20 desired to be prepared.

When it is desired to produce mainly lower olefins, such as ethene, propene and butenes, generally cracking temperatures in the range from 650° C. to 900° C., preferably from 700° C. to 800° C., are employed and residence 25 times in the cracking space varying from 3 to 0.001 seconds, preferably from 1 to 0.2 second, are used. Accordingly as the cracking temperature is selected higher, the residence time should be shorter to obtain optimal results. In actual practice there is a certain limit to the cracking temperature which should be as high as possible.

For the production of higher olefins, such as products rich in straight-chain olefins with more than 6 carbon atoms; lower cracking temperatures, namely, between 500° C. and 650° C., preferably between 550° C. and 600° C., are used while in that case residence times in the cracking space vary from about 20 to 0.5 seconds, preferably from about 5 to 1 seconds.

With a given system the residence time may be adjusted within the desired limits by means of the throughput rate, 40 and, if desired, by using diluents such as steam, nitrogen or gases obtained in cracking.

The use of diluents, though not necessary, is actually to be recommended, especially when high boiling residues are used as starting material, since they promote efficient 45 evaporation of the initial material. Steam is a particularly suitable diluent as this can easily be separated from the reaction products and has the additional advantage of preventing any carbon deposits liable to be formed in the cracking zone after a long running time.

The process according to the invention, which is usually applied under atmospheric pressure, but which may be performed at a higher or lower pressure as well, can, for instance, be carried out by passing the material to be cracked, preferably in a preheated state, in conjunction 50 with the oxidizing gas and any diluent that may be applied, at the desired rate through the heating zone containing a fixed substance having a large surface area and being an oxidation-promoting solid, after which the vapor mixture thus heated to cracking temperature is passed into the

55 cracking zone in which it remains for the required time, the reaction product effluent from the cracking zone being then quickly cooled or quenched, which is conveniently effected by direct contact with a coolant, for instance, water, cooled inert refractory pebbles, cooled inert finely divided refractory material in a fluidized bed, and the like.

Depending on the reaction conditions applied, the process of the invention yields products which are rich in olefins and consist mainly of lower olefins such as ethene, propene, butenes and the like (which may be 60 converted into valuable derivatives of various kinds, for example, saturated or unsaturated halohydrocarbons, alcohols, etc.) or consist to a large extent of higher olefins which may also be used for preparing valuable derivatives. Thus the higher straight-chain olefins, for example, those boiling between about 145 C. and 300° C., are an excellent

lent starting material for the production of secondary sulfuric acid alkyl ester salts, for instance, secondary sodium alkyl sulfates having an excellent detergency, while the higher branched olefins, which are also formed, are, for example, suitable for use as initial material for preparing alkyl aryl sulfonates possessing also good surface-active properties.

Another field of application of the higher olefins obtained by the practice of the invention is the production of products intended for use as lubricating oil additives, for instance, calcium alkylsalicylates.

The process according to the invention will be further described by means of the drawing which schematically illustrates a preferred mode of operating the process. A hydrocarbon feed which may suitably be a paraffinic oil containing about 15% by weight of aromatics and boiling above 500° C. is passed by line 11 through preheating zone A, in which it may be preheated to 100° C. From zone A, the feed passes in liquid phase through line 12 into heating zone B. Combustion sustaining gas enters the system through line 13 and header 14. The gas, which may be, for example, air or oxygen, may be passed directly into heating zone B by opening valve 15 in line 16 or it may be admixed with the hydrocarbon feed ahead of the heating zone by opening valve 18 in line 19 to introduce the gas into line 12. The section of line 12 from the intersection with line 19 to the point at which it enters the heating zone may represent a suitable oil burner. A diluent, such as steam, may be added, if desired, by introducing it through line 20 into header 21 from which it may pass to line 12 by opening valve 26 in line 22 or it may pass into heating zone B by opening valve 28 in line 24. There are known to the art numerous methods for introducing a liquid or vaporous oil feed into a combustion zone, either in previous admixture with combustion supporting gas or in such a manner that the oil and combustion supporting gas are admixed in the combustion zone, and either with or without the addition of diluent gas. Heating zone B is filled with a bed of particulate oxidation promoting solid, 30, e. g. a catalyst consisting of 95% by weight of activated alumina and 5% by weight of vanadium pentoxide. The catalyst bed may be separated from the cracking zone C by a separating member 31 which may be a wall with suitable openings to permit passage of the mixture of oil vapors and combustion gases from zone B into zone C. Cracking zone C will ordinarily be an open space confined by a wall 32 of material resistant to moderately high temperature, e. g. ordinary steel. Similarly, heating zone B will be confined by a wall of high temperature resistant material, e. g. ordinary steel which may be lined with a refractory material such as fire brick. The mixture of combustion gases and oil vapors is retained in the cracking zone C for a sufficient length of time, in the range stated, to produce a substantial amount of olefinic material. The reaction mixture is then withdrawn through line 34, where it is immediately quenched in quenching zone D by injecting a quench fluid through line 35. The quench fluid may be, for example, liquid water. The quenched mixture is then passed through line 34 to suitable condensation, separation and recovery equipment, not shown, to recover ultimately as product of the operation olefinic materials such as normal alkenes.

The process according to the invention will be further illustrated by reference to some examples.

Example I

A paraffinous oil residue having an aromatic content of 15% by weight and boiling above 500° C. was preheated to 100° C. and the material thus melted was passed, at the rate of 600 grams per hour, together with 100 liters of oxygen and 360 grams of water per hour, through a heating space filled with 100 ml. of catalyst consisting of 95% by weight of activated alumina and

5% by weight of vanadium pentoxide, and which had been preheated to 400° C.

The temperature in the catalyst bed rose to 750° C. The paraffinous residue, of which 9% by weight was burned to form water and carbon dioxide, was thereby heated in a period of 0.05 second from 100° C. to 750° C. The vapor mixture flowing from the heating space passed through a cracking space having a capacity of approximately 800 ml., the residence time therein being 0.4 second and the temperature having dropped to about 700° C. when the effluent flowed out. In this case there was obtained a product of which 70% by weight boiled below 30° C. This product boiling below 30° C. amounted to 61% by weight, calculated on the starting material.

The ethene-ethane fraction was 90% by volume ethene and 10% by volume ethane. The propene and the butene fraction were practically 100% olefins.

Calculated on initial material there were formed: 7% by weight of methane-hydrogen fraction, 26% by weight of ethene-ethane fraction, 15% by weight of propene fraction and 13% by weight of butene fraction.

Example II

A paraffinous oil residue boiling above 500° C. and having an aromatic content of 10% and consisting for the rest mainly of branched paraffins, was preheated to 100° C. The starting material, thus melted, was passed at the rate of 500 grams per hour, together with 80 liters of oxygen and 300 grams of water per hour, through a heating space filled with 100 ml. of a catalyst consisting of 95% by weight of activated alumina and 5% by weight of vanadium pentoxide and which was preheated to 400° C.

The temperature in the catalyst bed rose to 620° C. Of the hydrocarbon material, 10% by weight was burned to form water, carbon dioxide and carbon monoxide. The temperature rose thereby in 0.05 second from 100° C. to 620° C. after which the mixture was kept for a further 1.5 seconds in a cracking space having a capacity of about 3 liters, from which it was withdrawn at a temperature of approximately 600° C.

Of the product obtained a part corresponding to 26% by weight, calculated on starting material, boiled below 30° C. The portion boiling above 30° C. yielded on distillation 17% by weight (calculated on starting material) of a distillate, boiling between 30° C. and 300° C. This distillate contained 13.7% by weight (calculated on starting material) of a fraction boiling between 145° C. and 300° C. This fraction had a bromine number of 81 corresponding to a mono-olefin content of 78% by weight, the content of olefins with straight chain being 52% by weight. This fraction was suitable for use as initial material for preparing secondary sulfuric acid alkyl ester salts.

Example III

As starting material use was made of a paraffinous material boiling between 350° C. and 450° C. (obtained by dewaxing a light lubricating oil fraction) having an aromatic content of 3% by weight and an n-paraffin content of 85% by weight and for the rest consisting of naphthenes and isoparaffins.

This material was preheated to 100° C. and passed at the rate of 500 grams per hour, together with 80 liters of oxygen and 300 grams of water per hour, through a heating space filled with 100 ml. of a catalyst consisting of 95% by weight of activated alumina and 5% by weight of vanadium pentoxide.

The temperature rose thereby in the catalyst bed to 620° C. and 10% by weight of the hydrocarbon material was burned to form water, carbon dioxide and carbon monoxide. The temperature rose in this case in 0.05 second from 100° C. to 620° C. after which the vapor mixture was kept for a further 1.5 seconds in a cracking

space having a capacity of approximately 3 liters, from which it was withdrawn at a temperature of 600° C.

Of the product obtained a part corresponding to 25% by weight of the starting material boiled below 30° C.

The portion boiling above 30° C. gave on distillation 18% by weight (calculated on starting material) of a distillate boiling between 30° C. and 300° C. This distillate contained 14% by weight (calculated on starting material) of a fraction boiling between 145° C. and 300° C. with a bromine number of 85 corresponding to a mono-olefin content of 87% by weight, while the content of straight-chain olefins amounted to 75% by weight. This fraction was suitable for use as initial material for preparing secondary sulfuric acid alkyl ester salts.

We claim as our invention:

1. A process for preparing olefins by cracking high boiling hydrocarbons while suppressing side reactions which comprises passing a high boiling hydrocarbon mixture containing less than 25% by weight of aromatics together with a minor proportion of combustion sustaining gas through a relatively small heating zone containing a bed of particulate oxidation-promoting solid under conditions for essentially complete combustion of a portion of the hydrocarbon mixture and for quickly raising the temperature thereof to at least 500° C., and immediately thereafter passing the resulting mixture effluent from the heating zone through an unobstructed cracking zone whose capacity is at least eight times that of said heating zone for a short residence time therein wherein essentially only thermal cracking conditions are maintained, cooling the effluent cracked products from the cracking zone below cracking temperature, and recovering olefins from the product.

2. A process according to claim 1 wherein said combustion sustaining gas is free oxygen.

3. A process according to claim 2 wherein said oxidation promoting solid comprises vanadium pentoxide supported on a carrier having a large active surface area.

4. A process according to claim 2, wherein the heating of the hydrocarbon mixture in the heating zone is effected within one second.

5. A process according to claim 4, wherein the temperature to which the hydrocarbon mixture is heated in the heating zone is between 650° C. and 900° C. and the residence time in the cracking zone is between 3 and 0.001 seconds said recovered olefins being mainly normally gaseous olefins.

10 6. A process according to claim 4, wherein the temperature to which the hydrocarbon mixture is heated in the heating zone is between 500° C. and 650° C. and the residence time in the cracking zone is between about 20 and 0.5 seconds said recovered olefins being mainly normally liquid olefins.

15 7. A process according to claim 6, wherein the hydrocarbon mixture contains more than 40% by weight of paraffins and no more than 15% by weight of aromatics.

20 8. A process according to claim 2, wherein the high boiling hydrocarbon is a residue boiling above 450° C. and obtained in the distillation of mineral oils.

9. A process according to claim 2, wherein the heating and cracking are effected in the presence of added steam.
